UNITED STATES PATENT OFFICE.

JOHN A. PYPER, OF LONG BEACH, CALIFORNIA.

MULTIPLE-HANGER SUPPORT.

Application filed November 18, 1921. Serial No. 516,172.

To all whom it may concern:

Be it known that I, JOHN A. PYPER, a citizen of the United States, residing at Long Beach, in the county of Los Angeles and 5 State of California, have invented new and useful Improvements in Multiple-Hanger Supports, of which the following is a specification.

My invention relates to clothes hangers 10 particularly designed, although not necessarily, for use in conjunction with wardrobe trunks, and a purpose of my invention is the provision of a novel form of trouser or skirt hanger, and a support for sustaining a plurality of such hangers in proper position 15 within a wardrobe trunk.

I will describe one form of hanger and one form of support, each embodying my invention, and then point out the novel features in claims.

In the accompanying drawings,

Figure 1 is a view showing in front elevation a portion of a wardrobe trunk having applied thereto one form of hanger and support therefor, each embodying my invention. 25

Fig. 2 is a vertical sectional view taken on the line 2—2 of Fig. 1.

Fig. 3 is a horizontal sectional view taken on the line 3—3 of Fig. 1.

Fig. 4 is a fragmentary transverse sectional view taken on the line 4—4 of Fig. 3.

Fig. 5 is a sectional view taken on the line 5—5 of Fig. 1.

Fig. 6 is a view similar to Fig. 5 showing 35 a slightly modified form of stopping means for the support.

Fig. 7 is an enlarged detail view showing in top plan one of the hangers shown in Figs. 1 and 3.

Similar reference characters refer to similar parts in each of the several views.

Referring specifically to the drawings, my invention, in its present embodiment, comprises a support designated generally at S 45 designed for the purpose of supporting a plurality of skirt or trouser hangers designated generally at H in the same horizontal plane within a wardrobe trunk. This support, as illustrated to advantage in Fig. 2, comprises a U-shaped bracket 15 which is adapted to be secured to the inner side of a wardrobe trunk as clearly shown in Fig. 1. The opposite ends of the bracket 15 receive the ends of a pintle or pivot pin 16 upon 55 which are pivotally mounted a plurality of arms 17. Each arm is of substantially U

form with its free ends provided with suitable openings for receiving the pin 16 so that the arm as a unit is supported for swinging movement in horizontal plane. 60

As clearly shown in Fig. 2, the intermediate or vertical portion 17^a of each arm is of the same dimension, but the parallel portions 17^b progressively increase in length from the innermost arm to the outermost 65 arm with such portions provided with the necessary inclination so that their extremities can be mounted upon the pin 16. All except the innermost arm are formed with shoulders 17^c which allow of the accommodation 70 of the portion 17^a of the adjacent arm so that all of such portions are disposed in one and the same horizontal plane.

In the applied position of the support as shown in Figs. 1 and 2, any one arm 17 is 75 capable of being swung from a position contiguous and parallel to the adjacent end wall of the trunk outwardly to an angular position to permit the application or removal of the corresponding hanger H. To limit this 80 outward swinging movement, the bracket 15 is provided with a lip 18 which provides a stop against which the extremities of the arm are adapted to abut as they are swung outwardly. 85

In Fig. 6 I have shown a slightly modified form of bracket in which the lip 18 is dispensed with, and the extremities of the several arms are provided with an angular portion 19 adapted to engage the vertical 90 portion of the bracket 15 when the arms are in fully extended position thereby defining the outermost positions of the arms.

It is also desirable, and in fact necessary, to limit the inward swinging movement of 95 the arms in order that the support will properly sustain the hangers H. To this end each arm is provided with a stop pin 20 which, as illustrated to advantage in Fig. 4, spans the side portions of the arm and is 100 adapted to be received in suitable recesses 21 formed in the adjacent arm thereby limiting the inward swinging movement of such arm. In other words, that arm encompassing or surrounding the adjacent arm carries the 105 stop pin 20 and thus limits the inward movement of such arm. It will of course be noted that the inward movement of the innermost arm is limited by virtue of the bracket 15.

As illustrated to advantage in Fig. 7, 110 each hanger H comprises a pair of strips of wood or the like 22 riveted at one of

their ends to each other and to a plate 23 having the ends thereof interposed between the strips. The plate 23 is bent medially of its ends to provide a sleeve 24 in which a 5 pivot pin 25 is permanently secured so that its ends project from the opposite ends of the sleeve. The other ends of the strips 22 can be separated to allow the insertion of skirts or trousers therebetween, and after 10 the garment has been applied they can be contracted so as to clamp the garment by latch ring 26 swingingly mounted on a plate 27 and adapted to engage a hook or projection 28. As shown in Fig. 1, the hangers 15 may carry an eye 29 adapted to receive the hook 30 of a conventional form of coat hanger 31.

In the applied position of any one hanger H to any one arm 17, the upper end of the 20 pin 25 is insertable in an opening 32 of the arm, while the lower end is insertable in a slot 33 of the same arm. By so associating the pin with the arm, the hanger as a unit is supported for swinging movement 25 upon the arm so as to facilitate the application or removal of garments to and from the hanger.

In the application of the support S and the several hangers H to a wardrobe trunk, 30 it is preferable that a strip 34 be secured to the inner side of the trunk and at that side opposite from the support S. This strip 34 is designed to support the free ends of the several hangers H at the same time permitting of the free outward swinging movement of the hangers for obvious purposes. By virtue of the construction of the several 35 arms 17, it will be clear that all of the hangers H are capable of being swung to a point exteriorly of the trunk, it being particularly noted that the hangers can be swung independently of the arms. The construction of the support and hangers manifestly 40 renders it possible of their application to wardrobe trunks of standard form or to the usual construction of box trunks, thus converting the latter into a wardrobe trunk.

Although I have herein shown and described only one form of hanger and one 50 form of support each embodying my invention, it is to be understood that various changes and modifications may be made herein without departing from the spirit of the invention and the spirit and scope of the 55 appended claims.

What I claim is:

1. In combination, a support comprising 60 a plurality of arms progressively increasing in length and mounted to swing about a common axis, hangers each including a pivot pin, and a slot and opening in each of said arms for receiving each of said pins

whereby the hanger is pivotally and detachably supported on said arm. 65

2. A support of the character described 65 comprising a bracket, a plurality of arms, said arms being of substantially U-shape form and progressively increasing in length to allow the nesting of one arm within the other, and stop pins carried by certain of the arms adapted to engage in recesses formed in adjacent arms for limiting the swinging movement of said arms in one direction.

3. A support of the character described 75 comprising a bracket, a plurality of arms, said arms being of substantially U-shape form and progressively increasing in length to allow the nesting of one arm within the other, stop pins carried by certain of the 80 arms adapted to engage in recesses formed in adjacent brackets for limiting the swinging movement of said arms in one direction, and a lip formed on said bracket for limiting the swinging movement of said arms in 85 the other direction.

4. In combination, a support comprising a plurality of substantially U-shaped arms progressively increasing in length and mounted to swing about a common axis, 90 hangers each including a pivot pin, and a slot and opening in each of said arms for receiving each of said pins whereby the hanger is pivotally and detachably supported on said arm. 95

5. In combination, a support comprising a plurality of substantially U-shaped arms progressively increasing in length and mounted to swing about a common axis, hangers pivotally and detachably supported 100 on said arms, and means for limiting the swinging movement of said arms in one direction in which the arms occupy a nesting position so that the hangers can occupy parallel spaced positions. 105

6. In combination, a support mounted for movement, a pin in the support, and a clothes hanger comprising jaws, a split sleeve connecting the jaws and embracing said pin, and means for securing the jaws 110 in closed position.

7. In combination, a support comprising a plurality of arms progressively increasing in length and mounted to swing about a common axis, hangers pivotally and detachably supported on said arms, and means 115 for limiting the swinging movement of said arms in one direction in which the arms occupy a nesting position so that the hangers can occupy parallel spaced positions. 120

In testimony whereof I have signed my name to this specification.

J. A. PYPER,
